United States Patent Office.

W. Y. WARNER, OF WILMINGTON, DELAWARE.

Letters Patent No. 78,161, dated May 19, 1868.

IMPROVED SNOW-PLough.

The Schedule referred to in these Letters Patent and making part of the same.

TO ALL WHOM IT MAY CONCERN:

Be it known that I, W. Y. WARNER, of Wilmington, New Castle county, Delaware, have invented an Improvement in Removing Snow and Ice from Railway-Tracks; and I do hereby declare the following to be a full, clear, and exact description of the same.

My invention consists of the combination of a steam-boiler and steam-pipes applied to a car, as fully described hereafter, for the purpose of melting the snow or ice that may lie upon or between the rails of a railway-track.

In order to enable others skilled in the art to make and use my invention, I will now proceed to describe its construction and operation, reference being had to the accompanying drawing, which forms a part of this specification, and in which—

Figure 1 is a sectional elevation of my improved apparatus for removing snow or ice from railway-tracks.

Figure 2, a transverse section of the same on the line 1-2, fig. 1; and

Figure 3, an inverted plan view.

Similar letters refer to similar parts throughout the several views.

The apparatus is mounted upon a car or truck, of which α α are the wheels, and B the floor or platform. A steam-boiler, A, rests upon and is secured to the platform, its fire-box, b, passing through an opening in the latter, as shown in fig. 1, and directly over the fire-box is a steam-drum, C, and near the front portion of the boiler a water-tank, D.

To the under side of the platform, B, of the car, and extending around three sides of the same, as shown in the inverted plan view, is secured a steam-pipe, E, and projecting downward from the latter, at points directly over the railway-track, and at equal distances apart, are a number of smaller pipes or jets, c, open at their lower ends, as shown.

The pipe E is supplied with steam by a tube, d, leading from the steam-drum; and from the opposite side of the latter passes a similar tube, d', which supplies steam to one end of a pipe or series of pipes, F, running in a zigzag direction beneath the car, and supported by braces, e, at a point as close to the track as they can with safety be placed.

The opposite end of the pipe F communicates with the water-tank D by means of a pipe, f, as shown in fig. 2, for a purpose described hereafter.

The pipes below the platform and the wheels of the car are enclosed in a sheet-metal casing, G, secured to the sides and ends of the platform; and communicating with the chamber thus formed beneath the car, and projecting upwards from the platform, are two flues, H.

Before starting the car, steam is admitted into the pipes E and F, through the supply-pipes d and d', each of which is provided with suitable valves.

From the pipe E the steam passes into the jets c, and is discharged from the lower ends of each of the latter on to and between the rails of the track.

The steam also traverses, in a zigzag course, the whole length of the pipe F, in which course it becomes more or less condensed, and is finally discharged through the pipe f into the water-tank D, serving to heat the water in the latter so that steam may be made more rapidly.

After thus admitting steam to the several pipes, the car is moved slowly over the track, the snow or ice on the latter being effectually melted by the jets of steam discharged from the pipes c, and by the radiating heat of the pipe or pipes F.

The discharged steam, if permitted to escape from beneath and on all sides of the car, would interfere with the duties of the attendants, and be apt to frighten horses; it is therefore confined by the casing G, and caused to pass out above the car by the flues H.

The above apparatus is intended to be used either in connection with the snow-plough or not, according to the depth of the snow. It performs its work rapidly and thoroughly, and is equally adapted for horse or steam-railways.

I claim as my invention, and desire to secure by Letters Patent—

1. The steam-pipes F, arranged beneath the body of the car, parallel to the track, in combination with a pipe or pipes, E, having nozzles so arranged that steam may be discharged in a series of jets on to the track between the rails, as and for the purpose described.
2. The combination of the above and the water-reservoir D, as and for the purpose specified.
3. A casing, surrounding a track-cleaning apparatus, in combination with a flue or flues, H, arranged to conduct the vapors from the casing, substantially as and for the purpose set forth.

In testimony whereof, I have signed my name to this specification in the presence of two subscribing witnesses.

W. Y. WARNER.
